UNITED STATES PATENT OFFICE.

CHARLES G. OGLESBY, OF MEMPHIS, TENNESSEE, ASSIGNOR TO BUCYRUS COMPANY, OF SOUTH MILWAUKEE, WISCONSIN, A CORPORATION OF WISCONSIN.

TOWER-EXCAVATOR.

1,292,363.

Specification of Letters Patent.

Patented Jan. 21, 1919.

Application filed April 6, 1916. Serial No. 89,279.

To all whom it may concern:

Be it known that I, CHARLES G. OGLESBY, a citizen of the United States, residing at Memphis, in the county of Shelby and State of Tennessee, have invented a certain new and useful Improvement in Tower-Excavators, of which the following is a specification.

My invention relates to improvements in tower excavating machines wherein a track cable is suspended between two towers and excavator moved along the track cable as it performs the excavating, dumping and return movements. One object of my invention is to provide a type of tower excavator wherein the parts may be light, simple and cheap in construction and operation. Another object is to provide a device wherein the dirt may be easily and conveniently distributed and compacted. Other objects of my invention will appear in the specification. The invention is illustrated more or less diagrammatically in the accompanying drawing, wherein—

25 Figure 1 is a side elevation of the machinery with the work in section;

Fig. 2 is a side elevation on an enlarged scale of the bucket in the digging position; and

30 Fig. 3 is a detail showing the bucket in the hauling position.

Like parts are indicated by like letters throughout the several figures.

A is the dump. In the present instance it 35 is the levee which is being built by deposition of the material which is taken by the excavator from the channel or cut A¹. The head tower A² stands on the bank beyond the dump A. The tail tower A³ stands on 40 the opposed bank on the other side of the excavation A¹.

B is a track cable anchored at B¹ on the tail tower passing over a sheave B² at the top of the head tower and wound about a 45 winding drum B³ on the platform of the head tower so that manipulation of the winding drum will operate to slacken off or tighten up the track cable and thus raise or lower the trolley B⁴ which is suspended 50 therefrom and free to move therealong.

C is a haul back cable. This cable passes from the winding drum C¹ over a sheave C² at the top of the tower A² through the air to a return sheave C³ at the top of the tower 55 A³ and thence to the trolley B⁴ being at-

tached to the trolley and thus a rotation of the drum C¹ will tend to draw the trolley away from the head tower toward the tail tower.

D is an excavating bucket. It is suspended from a trolley B⁴ by a single line D¹ attached to the lower portion of the bucket at the rear. D² are guides on the rear end of the bucket to guide the line D¹. D³ is a downwardly projecting pivot shoe or runner 60 on the bottom of the bucket, located in front of the center of gravity of the bucket. D⁴ is the usual cutting edge and D⁵ a bail to which is attached the drag line D⁶. This drag line passes over the sheave D⁷ on the 65 tower A² and is controlled by the winding drum D⁸ in the usual manner. The winding drums are driven and controlled in any suitable way and for the sake of clearness and because the particular arrangement is not a 70 part of my invention, I have omitted the controlling means for driving the drums, this being in accordance with the usual practice.

It will be evident that while I have shown 80 in my drawings an operative device, still many changes might be made both in size, shape and arrangement of parts without departing from the spirit of my invention, and I wish, therefore, that my drawings be regarded as in a sense diagrammatic.

The use and operation of my invention are as follows:—

The two towers are arranged one on either side of the excavation and dump. The trolley is free to slide along the track cable. Starting with the parts in the position shown in dotted lines, the operator will tighten up on the track cable raising the trolley and bucket away from the ground. 90 The bucket will then be suspended in the position shown in full lines. The operator then starts the haul back cable meanwhile paying out the drag line and the trolley is thus dragged back along the track until 95 the excavator bucket is at the excavating point. The track cable is then paid out until the bucket rests on the ground the track cable being hauled tight enough to rock the bucket about the curved shoe or runner so 100 that the teeth or cutting lip is in engagement with the ground ready for cutting. The drag line is drawn in and the bucket is filled in the usual manner. If the surface is irregular or inclined it may be neces- 105

sary to manipulate the track cable during the excavating movement and this will be done so that the bucket will at all times when digging be in the position shown in 5 Fig. 2. When the bucket is filled the track cable is slackened off and the weight on the bucket rocks it about the shoe lifting the cutting lip out of contact with the ground. The load is drawn in until the dumping 10 point is reached, the bucket thus dragging along the ground. As soon as the dumping point is reached the track cable is tightened the bucket raised from behind into the dumping position as shown and then re-turned to the excavating point as above 15 pointed out.

The weight of the loaded bucket is never suspended by the track. The track cable has two functions. One of them to tilt up 20 the back end of the bucket so that excavating can take place, the other to permit convenient return of the light bucket to the excavating point. The bucket acts as an excavator, a carrier and as tamper and 25 smoother, since as it is dragged along the surface with its loads it tamps and smooths off the previously excavated material.

The height of the tail tower does not need to be as great as the head tower but 30 it must be great enough so that the track cable at the far side of the burrow pit or excavation be sufficient to enable the operator to tilt the bucket into the digging position by raising it.

35 The drag line and return line serve merely to move the bucket back and forth from the burrow pit to the dump. The manipulation of the track cable controls the bucket to make it perform all of the functions. 40 If the line is loose, the bucket slides along the ground without digging. If tightened a little the bucket digs or moves. If the cable is hauled clear up the bucket is emptied but at no time as above indicated is 45 the fully loaded bucket suspended on the track cable because the minute the dump commences the bucket begins unloading and before the bucket is lifted off the ground a large portion will be discharged and as this 50 operation occurs near to the head tower and the angles through which these loads are applied are favorable. The towers may be light and easily handled and constructed.

55 The shoe, of course, serves as a combined shoe and fulcrum and since it is in front of the center of gravity of the bucket causes the bucket to tilt back insuring the freeing of the cutting lip from the ground.

60 It will be noted that the line for lifting the rear end of the bucket is attached to the bottom of the bucket at a point inside of the back and the cable is carried around the back side of the bucket. The effect of this is that in all positions of the bucket 65 there is a large moment arm between the cen-

ter of gravity of the bucket and the pulling direction of this suspension chain. The promptness of the dump is directly proportional to the length of this arm, as it is the weight of the bucket and load multiplied by this distance which act to rotate the bucket into the dumping position. The same weight also tends to slide the trolley down the hill as soon as the track cable is tightened for the dump. Therefore, it is necessary that the bucket be suspended as far back of the center of gravity as possible to get it to dump before it has run any considerable distance down the sloping track cable. 70

75 It will be understood that the provision of the tail tower provides means for lifting the bucket clear of the ground at the extreme edge of the burrow pit thus permitting the bucket to be lowered into the digging position at the extreme back edge of the pit. The use of this tail tower also makes it possible to dump at any point in the embankment and by changing the tension in the track cable this dumping position may be 80 controlled by coöperation with this tower in any suitable manner. It will be understood also that the tail tower gives the flexible anchorage as a contrast with the rigid anchorage thus saving any wear and tear 85 on the machinery and making it much more smooth in its operation.

90 The track cable in my invention, therefore, has several functions. It serves in addition to transporting a bucket, as a hoisting cable, 100 a lowering cable, dumping cable and controls the digging and performs all the functions of the separate cables usually used for these different purposes, thus by manipulation of the single cable the operator carries 105 on the usual excavating processes in the usual manner getting the same general result as would be obtained if separate lines were used.

95 I claim:—

110 1. A drag line excavator comprising a drag bucket, a drag line attached to the forward end thereof, means for drawing in the drag line to move the bucket along the ground, a slack track line suspended above 115 the bucket, means for varying the tension in the track line to raise and lower it, a trolley movable along the track line, means for drawing the trolley along the line in the opposite direction from the movement of the bucket in response to the drag line, curved guides extending upwardly along the rear wall of the bucket, and a lifting line anchored on the bucket at the lower ends of said guides adapted to lie within the guides 120 when the bucket is in the cutting and dragging position, the upper end of the line being anchored on the trolley.

125 2. A drag line excavator comprising a drag bucket, a drag line attached to the for- 130

ward end thereof, means for drawing in the drag line to move the bucket along the ground, a slack track line suspended above the bucket, means for varying the tension in 5 the track line to raise and lower it, a trolley movable along the track line, curved guides extending upwardly along the rear wall of the bucket, and a lifting line anchored on the bucket at the lower ends of said guides 10 adapted to lie within the guides when the

bucket is in the cutting and dragging position, the upper end of the line being anchored on the trolley.

In testimony whereof I affix my signature, in the presence of two witnesses, this 1st day 15 of April, 1916.

CHARLES G. OGLESBY.
